UNITED STATES PATENT OFFICE.

CHARLES FRANCIS BLOOM, OF PORTLAND, OREGON.

CENTRIFUGAL CASTING-MACHINE.

1,400,857.

Specification of Letters Patent. Patented Dec. 20, 1921.

Application filed February 7, 1920. Serial No. 356,898.

To all whom it may concern:

Be it known that I, CHARLES F. BLOOM, a citizen of the United States, and a resident of Portland, in the county of Multnomah and State of Oregon, have invented certain new and useful Improvements in Centrifugal Casting-Machines, of which the following is a specification.

My invention relates to improvements in metal casting apparatus, it being adapted more particularly for casting in dental laboratories, and it consists in the constructions, combinations and arrangements herein described and claimed.

15 The foremost object of the invention is to provide a preferably hand-operated casting machine, wherein the molten metal is forced into the crevices of the mold by centrifugal action.

20 The same object of the invention more specifically stated, consists in the provision of a hand-operated casting machine for dental purposes, wherein the flask or mold containing the molten metal is first elevated in the 25 vertical part of a subsequently semi-circular track, being gradually thrown outwardly along a spiral line until it reaches the end of said track where it is subsequently spun in a circle so as to force the metal into the 30 crevices by virtue of the centrifugal action.

35 A further object of the invention is to provide a loose driving connection in the extensible driving shaft, for the purpose of permitting the flask to begin assuming its centrifugal motion as soon as the casting arm begins to travel in an arc, as more fully explained below.

40 A further object of the invention is to provide novel means for releasing the main gear from the casting arm after the casting arm has reached the casting position at the end of the semi-circular track, so that the main gear may operate to spin the flask in a circle as described above, said means 45 consisting of long and short lugs on the gear, and a cam-actuated latch on the casting arm.

50 Other objects and advantages will appear in the following specification, reference being had to the accompanying drawings, in which—

Figure 1 is a side elevation of the improved casting machine, showing the casting arm and flask in the normal or starting position,

Fig. 2 is a side elevation of the frame, all 55 coöperating parts being removed,

Fig. 3 is a detail view of the main gear, illustrating the relative positions of the gear-carried lugs and the arm-carried latch, the shorter lug operating to raise the arm 60 through the connection of said latch,

Fig. 4 is a similar view of the main gear showing the casting arm-latch approaching the frame-carried cam,

Fig. 5 is a similar view of the main gear 65 showing how the latch is disengaged from the short lug by engagement with the aforesaid cam, so that the main gear can continuously rotate free of the latch and the now stationary casting arm,

70 Fig. 6 is a horizontal section showing the parts in the casting position, as indicated in dot and dash lines in Fig. 1,

Fig. 7 is a detail cross section taken substantially on the line 7—7 of Fig. 6, 75

Fig. 8 is a detail perspective view of a portion of the main gear, illustrating the long and short lugs referred to above, and

Fig. 9 is a detail diagrammatic perspective view showing how the long lug trips the 80 latch in passing.

In carrying out my invention I provide a frame 1, to be affixed to a bench or other suitable place, provided with a central journal 2 and a semi-circular track 3, the major 85 portion of which is concentric with the journal 2 but the left extremity extending tangentially therefrom so as to provide the vertical starting portion 4. The circular part of the track occupies approximately 225° 90 of a circle, terminating at the right in a rounded end in which the guide roller 5 of the extensible end 6 of the casting arm 7 reclines when the final spinning or casting position is reached.

95 The journals, or more properly designated bearings, support a main shaft 8, which is fixed therein by the means 9, and has a head 10 to prevent the main bevel gear 11 from coming off. The main gear has a handle 100 12, by which the gear is rotated on the fixed main shaft 8, the casting arm 7 having an extension 13 which has bearing on that portion of the shaft between the members 2 of the frame, as clearly shown in Fig. 6.

105 A circular portion 14 of the end 6 occupies a corresponding bore in the arm 7 so that the end 6 may slightly extend as the

guide roller 5 rides from the circular track 3 into the vertical portion 4 upon the return of the casting arm to the original or starting position. The end 6 is bifurcated to straddle the track portion of the main frame.

At the extremity the bifurcated end 6 has bearings 15 in which the casting shaft 16 is rotated, to spin the flask 17, hung on the crank end 18, in a circle and thereby force the molten metal into a mold carried by the flask. This forcing of the molten metal occurs by centrifugal action, as the reader will readily understand. The turning of the shaft 16 is accomplished by means of the main gear 11, already mentioned, its companion driven pinion 19, the two-part extensible driving shaft 20, and the meshing gears 21, 22 respectively carried by the shafts 20 and 16. The frame 3 includes a rest 3^a in which the shaft 16 is spun in the final casting position.

A sleeve 23, fixed to the right shaft end in Fig. 6, covers the overlapping split ends of the extensible driving shaft. This sleeve is located between the lugs 24, 25, respectively on the arm 7 and extension end 6, in which the shaft 20 is journaled. The driving pinion 19 is loose on its shaft, but it has a tooth 26 engageable with a similar tooth 27 on a collar integral with the adjacent portion of the shaft, for the purpose of perfecting the necessary driving engagement. This tooth arrangement is in effect a clutch, the purpose of the loose play being to permit the flask 17 to commence its centrifugal motion as soon as the circular part 3 of the track is entered, because up to the time when the final dotted line casting position is reached in Fig. 1, the main gear 11 is locked in connection with the casting arm 7 by means of the latch 28, so that no turning of the driving pinion 19 can result until that latch is released.

The raising of the flask 17 along the straight portion *a* of the line indicating the path of movement of the flask in Fig. 1, is traversed quickly enough, so that by the time the circular track 3 is reached, the centrifugal motion or outward throwing of the flask will be commenced. It is therefore necessary to make provision for this tendency, and this provision consists in the loose clutch arrangement just described. The tooth 27 departs from the tooth 26 and is enabled to make substantially a full revolution of the shaft 20, so that ample play for the centrifugal or throwing motion of the flask 17 is provided.

The latch 28 is pivoted at 29 in the pocket 30 of the arm 7, the inner end extending into the adjacent opening which is entered by the cam 31 of the frame 1 when the final casting position is reached, to slightly rock the latch and disengage its outer head from the short conveying lug 32. This displace-

ment of the head of the latch is not sufficient to move it out of registration with the longer returning lug 33, both of which lugs are cast integrally on the inside of the main gear 11 as clearly shown in Fig. 8.

Pressing against the latch 28 is a leaf spring 34. This spring returns the latch to its normal position so that its head returns between the two lugs as shown for example in Fig. 3, and also permits a slight additional movement of the latch each time the rounded under portion of the returning lug 33 strikes the head of the latch, this occurring once in every revolution of the main gear.

The operation may be briefly reviewed to advantage. The normal position of the flask 17 and of the casting arm 7, with its carried parts, is indicated in full lines at the left of Fig. 1. It is while in this position of the flask 17, that the metal is melted in a crucible-shaped depression in the top of the flask.

Consider Fig. 3. The short conveying lug 32 is disposed beneath the latch 28, the head of which is then between the lugs 32, 33. The operator grasps the handle 12 and turns toward the right. The lug 32 causes the lifting of the casting arm 7, the guide roller 5 moving through the vertical portion 4 of the track. The telescopic portion 14 of the end 6 of the casting arm 7 is so provided that the vertical portion 4 of the track may readily be traversed by the guide roller, as is plain without further description.

After the flask 17 has been lifted approximately to the distance *a* in Fig. 1, it commences an outward movement indicated by the spiral line *b*. Such action taking place, the lug or tooth 27 departs from the tooth 26 permitting this movement of the flask, which terminates in the spinning zone *c* in Fig. 1. No turning of the driving pinion 19 through the main gear 11 can result until the latch 28 is moved from between the lugs 32-33, this particular connection being the means whereby the casting arm 7 is conveyed from one to the other extreme position.

But as soon as the dotted line position in Fig. 1 is neared, the fixed cam 31 is engaged by the inner end of the latch, causing that latch to rock on its pivot 29 so that its outer head is displaced from between the two lug sections. It is now easy to see that the operator may continue to turn the handle 12 in the clockwise direction because the short conveying lug 32 will pass without striking the head of the latch.

Of course the longer latch is still in the way, but its rounded under portion simply glides over the head of the latch, causing it to give against the tension of the spring 34, and thereby easily pass. The operator continues to turn the handle 12, thereby spinning the flask 17 in the circle *c*, until he

thinks the molten metal is perfectly impressed in all of the crevices of the mold.

He thereupon reverses the operation, turning the handle 12 toward the left or in the 5 counterclockwise direction, whereupon the returning lug 33, being still in coincidence with the head of the latch 28, lifts the casting arm 7 and returns the flask 17 to the original position. As soon as sufficient lift- 10 ing movement has been gone through, the inner end of the latch 28 escapes the cam 31, and when the friction between the lug 33 and the head of the latch is sufficiently re- 15duced, the spring 34 forces the head back to its original position between the two lugs.

While the construction and arrangement of the improved centrifugal casting machine as herein described and claimed, is that of a generally preferred form, obviously modifications and changes can be made without departing from the spirit of the invention 20 or the scope of the claims.

I claim:—

1. Casting apparatus, comprising means 25 carrying a flask with a mold in top of which metal is melted, and means on which it is operated to spirally approach a stopping position for the carrying means and spinning position for the flask.

2. Casting apparatus, comprising means carrying a flask with a mold and molten metal, means for moving said carrying means to a casting position, and means associated with said moving means, then becoming operative to spin the flask in a circle. 30

3. Casting apparatus, comprising an arm carrying a flask with a mold and molten metal, arm-associated flask-rotating means, including locking means enabling the raising 40 of the arm and flask from an initial loading position to a secondary casting position; and relatively fixed means then displacing said locking means to permit spinning of the flask through the then freed rotating means.

4. Casting apparatus, comprising an arm initially located, carrying a flask with a mold and molten metal; arm-carried flask-rotating means, with independently mounted 50 actuating means, including means by which the latter is normally locked to the arm to enable bodily conveyance of all the foregoing to a secondary casting position; and means stationarily located at that position, 55 for displacing the locking means to permit subsequent spinning of the flask through the actuating and rotating means.

5. Casting apparatus, comprising a flask- 60 carrying arm, and a main gear, each separately mounted; flask-rotating means on the arm and actuated by the gear, an arm-carried latch locking the gear and rotating means from movement relative to the arm during initial revolution of the gear to convey all 65 of the foregoing to a secondary casting po-

sition; and means stationarily located at that position, displacing the latch to free the gear from the arm then stationarily located, and permit subsequent spinning of the flask through the rotating means and 70 continued turning of the gear.

6. Casting apparatus, comprising a flask- 75 carrying arm, with flask rotating means including a loose driving pinion; a separately mounted meshing driving gear, locked to the arm by an arm-carried latch, to prevent gear and pinion movement relative to the arm during initial revolution of the gear to convey the foregoing parts to a casting position; and a clutch tooth connection between the driving pinion and its associated 80 rotating means permitting commencement of the flask-rotating function before the casting position is reached, and the gear is latch-released for subsequent rotation.

7. Casting apparatus, comprising movable 85 arm-carried flask carrying and rotating means, with actuating means normally locked to the arm; and a pinion also normally locked from operating said rotating means, loosely associated and having a normally open clutch arrangement enabling voluntary initial turning of said rotating means so that the flask may traverse a spiral line toward the final spinning and casting 90 position at the end of the arm movement.

8. Casting apparatus, comprising a frame with a circular track, a flask, a flask-carrying arm having a guide roller normally occupying one end of the track, with an associated gear, each separately mounted on the frame; arm-carried flask-rotating means, with a relatively loose driving pinion meshing with the gear; and including an arm-carried latch locking the gear and pinion 100 from movement relative to the arm during conveyance to the final casting position at the end of the circular track; and frame-carried means then displacing the latch to permit the continuance of gear revolution 105 and spinning of the flask in a zone gradually approached along a spiral line in following the track, through the loose connection of said driving pinion with its associated rotating means.

9. Casting apparatus, comprising a frame with a circular track including a vertical part, a flask, a flask-carrying arm having a guide roller normally occupying the vertical part, with an associated gear, each separately mounted on the frame; arm-carried flask-rotating means, with a relatively loose driving pinion meshing with the gear; and including an arm-carried latch locking the gear and pinion from movement relative to 110 the arm during conveyance to the final casting position at the end of the circular track; frame-carried means then displacing the latch to permit the continuance of gear revolution 115 and spinning of the flask in a zone 120 gradually approached along a spiral line in following the track, through the loose connection of said driving pinion with its associated rotating means.

125

gradually approached along a spiral line, through the loose connection of said driving pinion with its associated rotating means, and means located on the frame in 5 the casting position, providing a rest for the then stationary arm during the spinning of the flask.

10. In a casting machine, a frame having a circular track merging with an initially traversed vertical portion, and a casting arm revolubly mounted on the frame, with a portion carrying a guide roller in the track, telescopically mounted for extension when the roller enters said vertical portion.

15. 11. The combination in a casting machine, of a casting arm arranged to move through a part of a circle, and a flask-bearing end, bifurcated to straddle a frame portion, with a guide roller occupying a track in said 20 frame, and having a telescopic mounting on the casting arm to enable extension and retraction to follow the track.

25. 12. The combination in a casting machine, of a casting arm with a lug, an extension end telescopically mounted, with a lug, and end bearings; a casting shaft with a flask-carrying crank, journaled in the bearings and with a pinion; and a two-part driving shaft journaled in the lugs, one end with a 30 meshing pinion, and a covering sleeve between the lugs, extensible with said telescopic end to continuously maintain the driving connection.

35. 13. Casting apparatus, including a casting arm mounted to move through a part of a circle, with a carried latch; and an actuating gear having lugs with which the latch initially has locking engagement, for initially conveying the arm as stated through revolution of the gear.

40. 14. Casting apparatus, including a casting arm mounted to move through a part of a circle, with a carried latch; an actuating

gear having lugs with which the latch initially has locking engagement, for initially 45 conveying the arm as stated through revolution of the gear, and relatively stationarily located means for displacing the latch, permitting continued revolution of the gear while the casting arm remains stationary. 50

15. Casting apparatus, including a casting arm, with a spring-extended latch; an actuating gear, with long and short lugs between which the extended latch engages, for conveying the arm through part of a gear-revolution to a final casting position; and a cam relatively stationary at said position for retracting the latch sufficiently to clear the short lug and permit continued revolution of the gear, said latch springing over the 60 long lug when coming in contact once every revolution.

16. The combination in a casting machine, of a casting arm with a latch, and an operatively associated actuating gear, with a 65 short lug conveying the arm to a casting position by engagement with one side of the latch, and a long lug returning the arm to an initial position by engagement with the other side of the latch. 70

17. Casting apparatus, comprising supporting means having a track occupying part of a circle, with a rest adjacent one end; and means mounted on said support with parts moving in said track, for conveying a 75 flask in the direction of the track, terminating at said rest for subsequent rotation.

18. Casting apparatus, comprising supporting means having a track extending over part of a circle, with a rest adjacent one end; radially extending means for carrying a flask, guided in said track; and means at the track center where said means is journaled, for conveying it along the track to said rest for subsequent spinning. 80

CHARLES FRANCIS BLOOM.
